UNITED STATES PATENT OFFICE.

JENS SORENSEN, OF HARLAN, IOWA.

SALES-DISPLAY CABINET.

1,211,774.

Specification of Letters Patent.

Patented Jan. 9, 1917.

Application filed April 12, 1915. Serial No. 20,731.

To all whom it may concern:

Be it known that I, JENS SORENSEN, a citizen of the United States, residing at Harlan, in the county of Shelby and State of Iowa, have invented certain new and useful Improvements in Sales-Display Cabinets, of which the following is a specification.

This invention relates to a sales display cabinet for the use of grocers or other dealers in foodstuffs, and has for its object to provide a cabinet consisting of a plurality of connected sections for containing and displaying coffee or other articles of food, the construction being such that the contents may be conveniently removed when sold and that dust or foreign substances may be excluded.

The invention has especial reference to such an arrangement of parts that manufacture will be convenient and economical, and includes certain novel features of construction found to be of advantage which will be fully described in detail, illustrated in the drawings and pointed out in the claim.

In the accompanying drawing, Figure 1 shows a front elevation of the cabinet, parts of two of the sections being broken, and a part of a partition being in section. Fig. 2 is a plan view of the cabinet, the glass for the top of two of the doors being partly broken away. Fig. 3 is a sectional view on line 3-3 of Fig. 2. Fig. 4 is a detail relating to Fig. 3, showing the rear doors of a section, when opened. Fig. 5 shows a rear view of one of the sections and a broken away part of an adjacent section, the rear doors of a section being broken away to show the side plates for the lower door.

Referring now to the drawing for a more particular description, the display cabinet shown in Figs. 1 and 2 consists of any desired number of connected sections or compartments 6, these being rectangular in plan.

In order that the cabinet may be constructed economically an elongated base or bottom 7 is provided, upon which are secured the end plates 8 and the parallel, upright partitions 9.

Numerals 10 and 11 indicate grooved frame-strips which are secured upon the front ends of the end plates and partitions at their respective lower and upper edges, the front and rear ends of said plates and partitions being provided with facing strips

indicated respectively at 12 and 13, the facing plates 12 being provided with grooves.

Numerals 14 indicate glass plates which are mounted in the grooves of the frame strips and facing strips so that the contents of each section or compartment may be visible from the front.

At 15 are indicated parallel bearing strips, each being of T-shape in cross-section and secured upon the top of an end plate or partition. Rectangular frames are indicated at 16, each being provided with a glass plate 17, and the frames may have slidable movements to move rearwardly of the cabinet while disposed in the grooves between two adjacent T-shaped bearing strips, any projection of these frames forwardly of the front of the cabinet being prevented by the head-pieces *a* of each frame, since the head-pieces have a greater length than the width of frames 16 and are adapted to engage the rear convergent ends *b* of strips 15. The frames and glass plates operate to exclude dust or other objectionable substances, and while normally remaining closed, may be opened for purposes of filling the compartments or sections, if desired.

The rear facing-strips 13 have a greater length than strips 12, and the rear ends of the upright plates 8 and partitions 9 have a greater width than their front ends, with the result that frames 16 are disposed with a forward and downward inclination. The cabinet, when in use, is preferably placed on a counter (not shown) and when in this position the contents of the several compartments covered by the frames 16 and their glass plates, may be visibly inspected. However, since the contents of the compartments may have a dark color and the light may be absorbed, it is desirable to provide artificial light for each compartment, said artificial light also supplying a limited, uniform degree of heat required for safe storage of certain food products. For the purpose of supplying this artificial light, recesses 18 are formed in each partition to open on the rear end thereof, said recesses preferably conforming to the shape of the electric bulbs 19 which are inserted therein, a tube or conduit 20 for the wiring of the electric lights being disposed in recesses *c* opening on the top of the facing-strips 13.

In order that the contents of the compartments may be removed when sold, a

door 21 is provided for each, these doors being adapted to swing outwardly of the cabinet while mounted upon a pintle 22 having a length substantially equal to that of the 5 cabinet and secured upon the lower end of the facing strips adjacent to the base 7, each door 21 being provided with side plates 23 adapted to be disposed parallel with and adjacent to an end plate 8 or partition 9. Also 10 each side plate 23 is preferably of segmental form and is provided at its inner end at the terminal of its curved edge with a projection or catch 24 adapted to engage a lug or stop member 25 secured upon the facing 15 plates 9, to limit its outward swinging movement when opened for removing the contents of a compartment.

A second pintle is indicated at 26. It is disposed substantially parallel with pintle 20 22 and is secured to the facing plates 13, near their upper ends, and provides a mounting for the doors 27 with which the compartments are provided. The doors 27 may be swung upwardly to an open position to 25 permit ventilation when required, or for providing additional space when removing the contents of the compartments. It will of course be understood that instead of using the rear doors from time to time when 30 removing the contents of the compartments, such removal may be effected from the top of the cabinet, after sliding the frames 16 for that purpose.

As thus described the cabinet provides a 35 very convenient device for use in grocery stores since it is desirable that all food products, such as cereals, tea, coffee and many other articles be stored and sold in packages or kept under cover while exposed for sale. 40 In some instances it is necessary for the proper preservation of the goods that they should not be exposed to undue light or heat, and for that purpose a shelf 28 which is substantially horizontal may be provided for 45 each compartment and disposed near each frame 16, a vertical partition 29 being disposed adjacent to each glass plate 14 and arranged to support the shelf 28. By means of this construction that part of the contents 50 of the compartments disposed below shelves 28 may be protected from any excessive heat

occasioned by the electric lights, a portion or layer of the goods, identical with the goods mentioned, being disposed upon the shelf 28 and at the front of the partition 29, 55 where they may be seen or inspected.

Numeral 30 indicates an aperture formed in the front part of a shelf 28 so that the goods may be unloaded or deposited in the lower part of a compartment, whenever desired. 60

Numerals 31 indicate lids adapted to have 65 slideable movements in the parallel guides 32 mounted on the shelves 28, to close the apertures 30. Recesses 33 are provided in each 70 of the head pieces *a* of frames 16, in which price-cards 34 may be inserted.

What I claim and desire to secure by Letters Patent is,—

A sales display cabinet, comprising, in 75 combination with an elongated, rectangular base having vertical end walls and provided with intermediate walls parallel with the end walls to define a plurality of sections, rectangular, movable covers each having a 80 transparent part and disposed above a section, transparent plates disposed vertically between the front ends of said walls, non-transparent plates each having a height less than the height of said walls and disposed 85 adjacent to and parallel with the vertical, transparent plates, substantially horizontal shelves below said covers, each being provided with an aperture near its front end and a slide for closing said aperture and 90 connected with the upper end of a non-transparent plate to provide in combination therewith a lower compartment and an angularly formed upper compartment for each section, a hingeably mounted door at the 95 rear end of each section for making a closure for a lower compartment, and a hingeably mounted door at the rear end of each section for making a closure for an angularly formed upper compartment. 95

In testimony whereof, I have affixed my signature in presence of two witnesses.

JENS SORENSEN.
